(57) **CLAIM**

The ornamental design for an airport-lighting taxiway curve, as shown and described.

DESCRIPTION

FIG. 1 is a top, front, right perspective view of an airport-lighting taxiway curve embodying my new design; FIG. 2 is a top plan view thereof;

FIG. 3 is a front elevational view thereof;

FIG. 4 is an enlarged, cross-section detailed view taken along line 4-4 of FIG. 2; and,

FIG. 5 is an enlarged, cross-section detailed view taken along line 5-5 of FIG. 2.

The dash-dash broken line representations in the views are for the purpose of illustrating unclaimed environment of the claimed design. The dot-dash-dot broken line representations define unclaimed boundaries of the claimed design.

1 Claim, 3 Drawing Sheets(56)
